(57) **CLAIM**

We claim the ornamental design for a drive axle for dental or medical device, as shown and described.

DESCRIPTION

FIG. 1 is a perspective view of the drive axle for dental or medical device.

FIG. 2 is a left side elevation view thereof.

FIG. 3 is a right side elevation view thereof.

FIG. 4 is a top plan view thereof.

FIG. 5 is a bottom plan view thereof.

FIG. 6 is a rear elevation view thereof.

FIG. 7 is a front elevation view thereof;

FIG. 8 is a longitudinal section view thereof in elevation; and,

FIG. 9 is a perspective view of the drive axle of FIG. 1 in which the proximal end is fitted with a tool.

The broken line showings of the opening in the rear of the drive axle, the interior of the drive axle and the distal end of the drive axle form no part of the claimed design. The broken line showing of a tool illustrates the environment of the claimed design and forms no part thereof.

1 Claim, 5 Drawing Sheets
